Filed Mar. 2, 1959, Ser. No. 796,548

6 Claims. (Cl. 155—188)

This invention relates to a reversible, folding shelf structure, which can take up three different positions, namely a position in which the shelf hangs in a vertical plane, and two positions in which the shelf is supported horizontally, with either one of its sides facing upwardly.

The structure in accordance with the invention is of particular usefulness as a shampoo and utility tray for a beautician's chair. When used in this manner, one side of the shelf may be used as a shampoo tray and may be provided with a hinged shield having a neck receiving bay while the other side may be used as a utility table for dyeing and setting hair and like operations.

When not required, the shelf may be folded out of the way.

The structure in accordance with the invention includes a shelf and a support, which may be fixed to the back of a beautician's chair. The shelf is held by the support in cantilever position, at either of its two horizontal positions and the specific means for holding the shelf comprises U-shaped portions which engage a flat portion therebetween. More specifically, the support is made of a U-shaped bar, which in one position engages between the legs thereof a flat portion of the shelf, and in the other reverse position is itself engaged by a U-shaped portion of the shelf itself. Hinge means are provided to hold the shelf in its vertical folded position.

An embodiment of the invention is illustrated by way of example in the accompanying drawings, in which:

Figure 1 is a general perspective view of the shelf structure attached to a beautician's chair, in the position where it is used as a shampoo tray;

Figure 2 is a perspective view with the shelf in folded position;

Figure 3 is a fragmentary, vertical section of the shelf, in the position of Figure 1;

Figure 4 is a fragmentary, vertical section of the shelf, when used as a utility table, with the side opposite the shampoo tray facing upwards; and

Figure 5 is a fragmentary, vertical section of the shelf in the folded position of Figure 2.

In the views of Figures 3, 4 and 5, certain unessential background parts have been omitted, for the sake of clarity.

Referring to Figures 1 and 2, the shelf is formed of two panels, namely a solid panel 10, which can be seen in Figure 1, and a slotted panel 11 seen in Figure 2. At one end the panels 10 and 11 are interconnected by a continuous end portion 12 (Figures 3-5), and at the other end by open hinge portions 13. Preferably, as shown in particular in Figures 3-5, the shelf is formed of a single piece of sheet metal suitably bent to provide the end connection 12 and the hinge portions 13, said hinge portions being welded to the margin of the free end of panel 10, namely at 14, as shown in Figure 1. The resulting structure may thus be defined as two panels, held in spaced relation by end connections 12 and 13.

The support for the shelf is formed as a continuous

flat bar, bent to provide an upright 15, and two legs 16 and 17 of a substantially U-shaped portion. The upright 15, as shown in Figure 1, is held in position at the back of the chair by means of a bracket 18 having a set screw 19, which enables adjusting the position of the support. The upright 15, is preferably provided with a knee 20, the portion of upright 15 above the knee extending rearwardly.

As shown in Figures 3-5, the upper leg 17 of the U-shaped portion of the support comprises at the end thereof a transverse rod 21, which is adapted to engage the hinge portions 13, as in Figures 2 and 5, and thus to hold the shelf in its folded vertical position.

The panel 11 of the shelf, as shown in Figure 2, comprises a slot 22, of width slightly larger than the width of the bar out of which the support is made. The slot 22 is continued in the end connection defined by hinge portions 13, between said hinge portions, and the opposite end thereof is slightly spaced from the other end 20 of panel 11, such spacing being of approximately the same size, as the length of the U-shaped portion defined by legs 16 and 17.

The various positions of the shelf are clearly shown in Figures 3-5. Starting from the folded position of Figure 5, the shelf is revolved about the rod 21 through an angle of about 90°, and is then pushed towards the right of the drawing, until it reaches the position shown in Figure 4. In this position the marginal portion of panel 10 is held between the legs 16 and 17 of the support. To enable the shelf to be held securely in this position, wherein the shelf is used as a utility table, and may therefore have bottles and other objects placed thereon, a ratchet-tooth locking arrangement is provided. One tooth 23 is located on the inner face of the leg 16 of the support, while the other tooth 24 is located at a suitable position on the outer face of the panel 10. The tooth 24 is visible also in Figure 1. Teeth 23 and 24 engage each other when the shelf has reached the position of Figure 4, and may be disengaged by forcing upwardly on the shelf, so as to slightly spread apart the legs 16 and 17 of the support.

To place the shelf in its shampoo tray position, starting from the folded position of Figure 5, the shelf is revolved about rod 21 through approximately 270°, and is then pulled towards the left of the figure until the U-shaped support portion defined by legs 16 and 17 finds itself in the U-shaped portion defined by panel 10, end connection 12 and the solid portion of panel 11, this end position being shown in Fig. 3. It will be seen that, in reaching this position, the support has travelled through the whole length of the slot 22.

As shown particularly in Figure 1, the panel 10 has upstanding side walls 27, to channel the water into a sink, when the shelf is used as a shampoo tray. At the end of panel 10, adjacent the end connection 12 is hinged a shield 25 having a neck-fitting bay 26. The shield 25 is freely pivotable so as to be adjustable to various positions, said shield being held in these positions by contact with the neck of the person who is using the chair.

It will be seen that in the position of Figures 1 and 3, any rearward pressure on the shelf, such as may be exerted through the shield 25, will only tend to push the shelf backwards into even more firmly engaged position. To keep the shelf longitudinally aligned, ribs 28 are preferably provided in the U-shaped portion of the shelf, between panel 10 and the unslotted portion of panel 11, these ribs, as can be seen in Figure 2, being substantially in line with the edges of slots 22, so as to engage longitudinally the edges of legs 16 and 17 of the support.

The free edges of shield 25 and of walls 27 are preferably provided with protective resilient rims 29.

The embodiment of the invention which has been illustrated and described is given merely by way of example and various modifications thereof are possible within the scope of the appended claims.

I claim:

1. A folding shelf structure comprising a shelf and a fixed support, one of said shelf and said support comprising a generally U-shaped portion adapted to receive, between the legs thereof, a portion of the other of said shelf and said support, to hold said shelf in cantilever position, said support comprising a transverse rod and said shelf comprising an open hinge by which said shelf hangs from said rod in the folded position of said shelf and means guiding said shelf on said rod between said cantilever and said folded position.

2. A folding shelf structure comprising a shelf and a fixed support, said shelf comprising a U-shaped portion adapted to receive between the legs thereof a portion of said support, to hold said shelf in a first cantilever position, said support comprising a U-shaped portion adapted to receive between the legs thereof a flat portion of said shelf, to hold said shelf in a second cantilever position, said flat portion of said shelf being at the opposite end thereof from said U-shaped portion, said support comprising a transverse rod and said shelf comprising, adjacent said flat portion, an open hinge by which said shelf hangs from said rod in the folded position of said shelf and means guiding said shelf on said rod between said first and second cantilever positions and said folded position.

3. A reversible folding shelf structure comprising a shelf and a fixed support, said shelf comprising two spaced panels, end connections for said panels, one of said panels having a slot extending centrally over the major portion thereof and one of said end connections comprising a slot which is a continuation of said first mentioned slot; said support comprising a horizontally disposed U-bent bar, the legs of which are spaced by

a distance generally equal to the thickness of said unslotted panel, and define together externally a thickness generally equal to the spacing of said panels, a fixed upright member depending from the end of the lower leg of said U-bent bar, the width of said bar being smaller than the width of said slot, and a transverse rod attached to the free end of the upper leg of said bar; said rod being adapted to engage said slotted end connection, for pivotal movement of said shelf and said bar being moveable in said slot for sliding movement of said shelf between three positions: a first position in which said U-bent bar is engaged between said unslotted panel and the unslotted portion of said slotted panel; a second position in which said U-bent bar engages between the legs thereof a portion of said slotted panel; and a third position in which said shelf hangs by said slotted end connection from said transverse rod.

4. The structure of claim 3, further comprising a ratchet tooth on the outer face of the unslotted panel and a ratchet tooth on the lower leg of said support bar, said teeth being positioned to engage each other in said second position.

5. A structure as claimed in claim 3, for use as a shampoo tray wherein said unslotted panel has upstanding side walls, and has hinged at the unslotted end thereof a shield with a neck-receiving bay.

6. The structure of claim 3, further comprising ribs aligned with the edges of said slot, and transversely disposed between said unslotted panel and the unslotted portion of said slotted panel, to transversely secure said U-bent bar in said first position.
